UNITED STATES PATENT OFFICE

MARY E. CUSICK, OF PITTSBURGH, PENNSYLVANIA

DESIGN FOR A SHOE-DISPLAY STAND

Application filed August 29, 1929. Serial No. 32,598. Term of patent 7 years.

To all whom it may concern:

Be it known that I, MARY E. CUSICK, a citizen of the United States, residing at 1837 Chislett Street, in the city of Pittsburgh, county of Allegheny, State of Pennsylvania, have invented a new, original, and ornamental Design for a Shoe-Display Stand, of which the following is a specification, reference being had to the accompanying drawing, forming a part thereof.

The drawing is a perspective view of a shoe display stand showing my new design.

I claim:

The ornamental design for a shoe display stand as shown.

MARY E. CUSICK.
